CLAIM

The ornamental design for a handle for cleaning apparatus, as
shown and described.

DESCRIPTION

FIG. 1 is a front elevational view of the handle for cleaning
apparatus showing our new design;

FIG. 2 is a top, front, left side perspective view thereof;

FIG. 3 is a right side elevational view thereof;

FIG. 4 is a rear elevational view thereof;

FIG. 5 is a top plan view thereof; and,

FIG. 6 is a top, front, right side perspective view thereof.

The broken line showing of a cleaning apparatus in FIGS. 1-6
is included for the purpose of the environment of the handle
for cleaning apparatus and forms no part of the claimed
design.
